Herman Ihlenburg, by A. Sidney Green, Attm

UNITED STATES PATENT OFFICE.

HERMAN IHLENBURG, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 17,346, dated May 17, 1887.

Application filed March 16, 1887. Serial No. 231,216. Term of patent 14 years.

To all whom it may concern:

Be it known that I, HERMAN IHLENBURG, (assignor to the MACKELLAR, SMITHS & JORDAN COMPANY,) of the city and county of Philadelphia, Pennsylvania, have invented and produced a new Design for a Font of Printing-Type, of which the following is a specification.

The nature of my design is clearly shown in the accompanying typographic impression, to which reference is made; and it consists of an unshaded letter, in which, as in the A B D F L P R, the up-and-down portion of the letter turns to the right hand and terminates in the dot; the lower termination on the left hand of the A, F, H, J, K, M, N, P, S, and X is gradually widened, which feature is also found at the upper right hand of the C, E, G, K, S, T, and X; the lower termination of the G is ornamented by the curved line with the dot termination, which ornament is found in the H and the I, crossing the upper portion of the same; the M, U, and W are looped, as shown, and the A, G, H, I, K, X, and Y are ornamented at the base by the flourishes, as shown.

The character of the design is preserved in the lower-case, notably in the b, c, f, h, k, l, v, w, and z, and in the numerals.

Having now described my invention, I claim as new—

The design for a font of printing-type, as shown and described, the same consisting of an unshaded letter, in which, as in the A B D F L P R, the up-and-down portion of the letter turns to the right hand and terminates in the dot; the lower termination on the left hand of the A, F, H, J, K, M, N, P, S, and X is gradually widened, which feature is also found at the upper right hand of the C, E, G, K, S, T, and X; the lower termination of the G ornamented by the curved line with dot terminations, which ornament is also found in the H and the I, crossing the upper portion of the letter; the M, U, and W looped, as shown, and the A, G, H, I, K, X, and Y ornamented at the base by the flourishes, as shown, and the character of the design preserved in the lower-case, notably in the b, c, f, h, k, l, v, w, and z, and in the numerals.

HERMAN IHLENBURG.

In presence of—
HERMAN METIUS,
C. F. HUCH.
